CLAIM

The ornamental design for a [pliers] pair of handles for a pliers, as shown and described.

DESCRIPTION

FIG. 1 is a top plan view of a [pliers] pair of handles for a pliers showing my new design with the tool jaws closed, the bottom plan view being a mirror image thereof [ ], the portion in phantom forming no portion of my design;

FIG. 2 is a front elevational view thereof, the rear elevational view being a mirror image thereof, the portion in phantom forming no portion of my design;

FIG. 3 is a top plan view thereof with the tool jaws open, the bottom plan view being a mirror image thereof, the portion in phantom forming no portion of my design;

FIG. 4 is a side elevational view thereof as viewed from the left-hand side of FIG. 2 the portion in phantom forming no portion of my design; and,

FIG. 5 is a side elevational view thereof, as viewed from the right-hand side of FIG. 2.
